RETRACTOR BOLT

Homer Eichacker, Indianapolis, Ind., assignor to
 Vonnegut Hardware Company, Indianapolis,
 Ind., a corporation of Indiana

Application August 30, 1947, Serial No. 771,408

4 Claims. (Cl. 292—332)

1

The present invention relates to a latch bolt for swinging closures, and is particularly concerned with the provision of means, extremely simple and inexpensive, and yet faithful in performance and sturdy to resist wear and damage, for holding a latch bolt in retracted position during swinging movement of its associated closure; such means being of such character that the bolt is automatically released for projection when the closure is moved to closed position. Ancillary objectives will appear as the description proceeds.

To the accomplishment of the above and related objects, my invention may be embodied in the forms illustrated in the accompanying drawings, attention being called to the fact, however, that the drawings are illustrative only, and that change may be made in the specific constructions illustrated and described, so long as the scope of the appended claims is not violated.

Fig. 1 is a perspective view of a double swinging door equipped with panic latches, showing a typical installation of my retractor bolt;

Fig. 2 is a rear elevation of a latch bolt and housing usable at the bottom end of such a door;

Fig. 3 is a vertical section taken substantially on the line 3—3 of Fig. 2;

Fig. 4 is a front elevation of a latch assembly constructed in accordance with my invention and adapted for installation at the top of such a door;

Fig. 5 is a vertical section taken substantially on line 5—5 of Fig. 4;

Fig. 6 is a rear elevation of the assembly illustrated in Fig. 4;

Figs. 7, 8, and 9 are transverse sections taken, respectively, substantially on line 7—7, 8—8, and 9—9 of Fig. 6;

Fig. 10 is a broken perspective view of a preferred means for providing a connection between a pull rod and my rocking latch bolt;

Fig. 11 is a fragmental section taken in the plane of Fig. 5 and showing the parts in a different position of adjustment;

Fig. 12 is a perspective view of a modified form of retractor bolt; and

Fig. 13 is a vertical section through the assembly of Fig. 12.

Closure installations of the character illustrated in Fig. 1 are very common and well known in schools, auditoriums and other public buildings. The doorway is adapted to be closed by mating swinging doors 10 and 11, the door 10 being provided with latch bolts 12 and 13 at its upper and lower ends, and the door 11 being

2

provided with similar latch bolts 14 and 15. Each door is provided with a panic bar 16 or 17 constructed and arranged to operate pull rods 22 and 29 for retracting the bolts at the upper and lower ends of the doors.

Spring means is customarily provided for projecting the latch bolts into association with their sockets or keepers; and, unless special means is provided, that spring means will tend to hold the bolts in projected positions at all times except when pressure is being exerted against the associated panic bars 16 or 17.

Since there are many installations in which it is necessary or desirable to cause the lower bolts 13 and 15 to enter keepers such as 18, the top surfaces of which are flush with the floor surface 19, it will be obvious that unless retaining means is provided, the bolts 13 and 15 would frequently drag across the floor 19 during swinging movement of the closures 10 and 11.

Various forms of retainers have heretofore been devised; but, so far as I am advised, they have all involved relatively complicated trigger, cam, gear, or toggle mechanisms which not only are expensive to manufacture and assemble, but are subject to numerous disorders and may frequently jam as a result of the violent use to which panic latch mechanisms are frequently subjected.

I have devised an extremely simple, yet sturdy and effective means for holding the latch bolts in retracted positions from the time when such bolts are retracted by actuation of the panic bar until the closure with which the latch mechanism is associated is positively moved to closed position.

In the illustrated installation, a latch housing 21 is secured to that surface of the door 10 which faces in the direction of door-closing movement, and near the bottom end thereof. The pull rod 22 enters the top of the housing and within the housing is operatively connected to the upper end of the latch bolt 13, a spring 20 being confined between an abutment on said rod and the upper end of the housing 21 as shown. A screw 23 is set into one face of the bolt 13, the head 23 of said screw being cooperable with an abutment 24 formed on the housing to limit movement of the bolt 13.

The housing 21 may, if desired, be identical with a housing 25 secured to the same face of the door adjacent the upper end thereof and reciprocably receiving the latch bolt 12. The housing 25 is preferably formed to provide a

plane rear surface 26 adapted to seat against the door face.

The forward wall 27 of the housing 25 inclines upwardly and away from the surface 26, and is provided with an abutment 28 at its upper end projecting substantially horizontally toward the surface 26. The pull rod 29 enters the lower end of the housing and is operatively connected, within the housing, with the lower end of the latch bolt 12.

Said end of the latch bolt is bifurcated to provide furcations 30 and 31 straddling the upper end of the pull rod 29. As is most clearly shown in Figs. 5 and 10, a web 32 joins the lower ends of said furcations and is perforated to receive the rod 29. The upper surface of said web 32 is oppositely chamfered as at 33 on its edges facing the front and rear walls of the housing 25. Spaced slightly above the web 32, and joining the furcations 30 and 31, is a second web 34, likewise perforated for the accommodation of the rod 29, and the lower surface of this web is similarly oppositely chamfered as at 35. The rod 29 is formed, in the region adapted to be positioned between the webs 32 and 34, with transverse grooves adapted to receive the furcations of a bifurcated washer 36. It will be perceived that, for assembly, the space between the webs 32 and 34 may be brought into registry with the opening 37; the rod 29 may be entered in the perforations in said webs, with its grooves in registry with the space between said webs, and the washer 36 may be assembled with the rod and the bolt. Thereafter, the assembled parts are lifted and a screw 39 may be seated in a threaded bore in the rear surface of the bolt for cooperation with an abutment 40 to limit the throw of the bolt.

On its front surface, and near its outer end, the bolt 12 is provided with a transverse groove or notch 38, adapted, at times, to receive the rearwardly projecting abutment 28. A resilient leaf spring 41 is adapted to have its lower end 42 supported upon a transverse wall 43 formed on the housing; and said leaf is flexed by threading it outside a transverse bar 44 and inside a transverse bar 45 formed on the housing, the upper end 46 of said leaf bearing against the rear surface of the bolt 12 to urge said bolt to rock forwardly about its support upon the washer 36.

A strike or keeper 47 is adapted to be secured to the soffit stop 47' of the door frame in such a position as to cooperate with the bolt 12 when the door is closed. Said strike is formed to provide a wall 48 facing in the direction of door-closing movement and engageable by the bolt 12, when the latter is fully projected, to prevent opening movement of the door. The keeper 47 is so disposed as to locate the wall 48 in a plane spaced beyond the surface 48' of the soffit stop by an amount substantially equal to the distance between the rear surface of the bolt 12 and the adjacent surface of the door 10 when the parts are in the positions of Fig. 5. A lip 49 projects downwardly below the lower limit of the wall 48. It will be perceived that, when the bolt 12 is in retracted position, it will clear the wall 48, but will strike the lip 49.

When the bar 16 is actuated, the pull rod 29 retracts the bolt 12 to clear the wall 48. As the notch 38 comes into registry with the abutment 28, the spring 41 will cause the bolt to rock forward about its support upon the washer 36, thereby engaging the abutment 28 in the

notch 38 to hold the bolt in retracted position. Since the rods 29 and 22 are coordinated through the actuating mechanism associated with the bar 16, the bolt 13 will likewise be retained in retracted position.

The parts will remain in this condition until, upon closure of the door, the forwardly-leaning bolt 12 strikes the lip 49, just before the door comes into contact with the surface 48', whereby 14 the bolt will be arrested while the housing 25 continues to move, with the door 10, for a further fraction of an inch in door-closing direction. Thereby the notch 38 will be disengaged from the abutment 28, and the spring means 15 associated with the two bolts 12 and 13 will project said bolts to the positions of Figs. 3 and 5.

In Figs. 12 and 13, I have shown a simpler embodiment of my invention in which the housing 25 is replaced by a skeletal housing or bracket 20 55 formed to provide a toe 56 perforated at 57 to guide the pull rod 29'. The strap 58 guides the latch bolt 12', the lower end of which is bifurcated to straddle the upper end of the rod 29', and is pivotally connected thereto by a 25 pin 59, or the like. The forward surface of the bolt 12' is provided with a notch 60 cooperable with the front wall of the strap 58.

A leaf spring 61 may have one end secured, as by a screw 62, to the rear face of the bolt 30 12', its free end slidingly engaging the bracket 55 to urge the bolt 12' forwardly. The keeper 63 is similar to the keeper 48 providing a wall 64 engageable by the projected bolt 12' to prevent door-opening movement, but cleared by said bolt 35 when the bolt is in retracted position. A depending lip 65 is positioned to be engaged by the retracted bolt 12' when the door is closed, to disengage the notch 60 from the strap 58.

I claim as my invention:

40 1. A latch assembly comprising a housing adapted to be secured to a swinging closure, a latch bolt guided for reciprocation in said housing and projectible from one end thereof, said housing having an opening in one side thereof substantially coincident with said latch bolt and elongated in the direction of the path of said latch bolt, a rod extending into the opposite end of said housing, means providing a rigid push-pull connection substantially free from lost motion between said rod and said bolt while leaving said bolt free for limited rocking movement relative to said rod, about an axis transverse to the length of said housing opening and parallel to the plane thereof, in the direction of closure movement, said bolt being provided, in one face, 45 with a transverse notch opening in the direction of closure-closing movement, catch means on said housing adapted to enter said notch, when in registry therewith, a wall transversely arranged adjacent the base of said housing opening, a transverse bar projecting into said opening at a point spaced from said wall toward said one end of said housing, a second transverse bar projecting into said opening at a point between said first-named bar and said one end of said housing, and a leaf spring having one end supported on said wall, bearing against the outer surface of said first-named bar, bearing against the inner surface of said second bar, and disposed with its opposite end in flexed, frictional engagement with said latch bolt to urge the free end thereof in closure-closing direction.

55 2. A latch assembly comprising a housing adapted to be secured to a swinging closure, a latch bolt guided for reciprocation in said hous-

ing and projectible from one end thereof, said housing having an opening in one side thereof substantially coincident with said latch bolt and elongated in the direction of the path of said latch bolt, a rod extending into the opposite end of said housing, means providing a rigid push-pull connection substantially free from lost motion between said rod and said bolt while leaving said bolt free for limited rocking movement relative to said rod, about an axis transverse to the length of said housing opening and parallel to the plane thereof, in the direction of closure movement, said bolt being provided, in one face, with a transverse notch opening in the direction of closure-closing movement, catch means on said housing adapted to enter said notch, when in registry therewith, a wall transversely arranged adjacent the base of said housing opening, a bar transversely spanning said housing opening at a point spaced from said wall toward said one end of said housing and providing an abutment surface facing away from said latch bolt, a second bar transversely spanning said opening at a point between said first-named bar and said one end of said housing, and a leaf spring having one end supported on said wall, engaging said bar abutment surfaces intermediate its ends, and having its opposite end inflexed, frictional engagement with said latch bolt to urge the free end thereof in closure-closing direction.

3. The assembly of claim 2 in which said first-named bar is located closer to said latch bolt than is said second bar.

4. A latch assembly comprising a housing

adapted to be secured to a swinging closure, a latch bolt guided for reciprocation in said housing and projectible from one end thereof, a rod extending into the opposite end of said housing and formed, within said housing, with a transverse groove, a washer seated in said groove, said bolt having adjacent, oppositely-facing, trans-axial rocking surfaces closely embracing opposite surfaces of said washer, said bolt being provided, in one face, with a transverse notch opening in the direction of closure-closing movement, catch means on said housing adapted to enter said notch, when in registry therewith, and spring means cooperable with the opposite face of said bolt to urge the same in closure-closing direction.
